Attorney.

UNITED STATES PATENT OFFICE.

HANS HENRIK BLACHE, OF HELLERUP, NEAR COPENHAGEN, DENMARK.

INTERNAL-COMBUSTION ENGINE, WHICH MAY BE DIRECTLY REVERSED.

1,399,723.

Specification of Letters Patent.

Patented Dec. 6, 1921.

Application filed September 10, 1920. Serial No. 409,470.

To all whom it may concern:

Be it known that I, HANS HENRIK BLACHE, residing at No. 32 Sofievej, Hellerup, near Copenhagen, Denmark, have invented certain new and useful Improvements (for which I have filed application in Denmark on April 12, 1918) in Internal-Combustion Engines, Which may be Directly Reversed, of which the following is a specification.

10 In internal combustion engines, which may be directly reversed and which are controlled by valves, provision should be made for the opening of a valve or the like during the reversal in order to blow out the pressure within the cylinder so that after the reversal the engine may be started exactly similarly to the starting from rest-position.

The present invention has for its object the provision of means by which the blow-off valves are automatically opened during the reversing operation so that the pressure is equalized by said valves. For that purpose one part which is shifted during the reversing operation is connected with a pawl-arm 25 or the like, which during said operation acts on a roller on the lever controlling the blow-off valve, so that said valve is automatically opened during the reversing operation. Said pawl-arm or the like is arranged in such a 30 manner that it acts only on the blow-off valve during the reversing operation. When said operation is completed the pawl-arm is at once released from the roller of the valve-controlling lever.

35 A constructional form of the invention is illustrated in the accompanying drawing in which:

Figure 1 shows parts of an internal combustion engine provided with the improved 40 means and

Fig. 2 shows a detail thereof.

When the engine is running the different valves are operated by horizontal levers which are connected to vertical rods, the 45 lower end of each rod being provided with a roller co-acting with a cam on a rotary cam shaft.

When the engine is to be reversed, said vertical rods are moved out of engagement 50 with the cam-shaft which then is adjusted to bring into position the cams corresponding to the reverse running of the engine, whereupon the rollers of the vertical rods are brought in engagement with said cams. 55 a (Fig. 1) is the blow-off valve which is moved in the known manner from the hori-

zontal lever *b* pivotally mounted on the pivot *c* and pivotally connected to the vertical rod *d* provided with a roller *e*, which engages the periphery of the cam *g*, so that the 60 rod *d* is raised and lowered during the rotation of the cam shaft *f*. During the reversing operation the rods *d* are moved out of engagement with the cams *g* by links *h* connected to arms *i* on the reversing shaft *k* by 65 the rocking of which the rollers *e* are brought into or out of engagement with the cams *g*.

According to the invention a pawl-arm *l* is arranged below the lever *b*, having its fixed pivot *m* in a mounting on the cylinder 70 cover. The upper end of the pawl-arm is inclined and the lever *b* is provided with a roller *n* on which the pawl-arm acts when moved with the vertical rod *d*. The pawl-arm *l* is connected to the rod *d* by a link *o* 75 pivotally connected to said rod *d* by a pin *p*. In the form illustrated the pawl-arm is provided with a cylindrical part (see Fig. 2) inclosing a cylinder *r* connected with the pawl-arm by two pivots *s*. Within the cylinder *r* a coiled spring *q* is mounted, which spring is compressed when the link *o* is moved outward with the vertical rod *d*. During the outward movement the pressure of the spring *q* on the closed end of the cylinder *r* will move the pawl-arm *l* outward, so that the inclined upper end of said pawl-arm acts on the roller *n* thereby rocking the lever *b* to open the blow-off valve *a*. When the reversing operation is completed the rod 80 *d* is moved inward. By this movement the pawl-arm *l* is moved back to release the roller *n* so that the lever *b* again can operate the valve normally. If the lever *b*, when the reversing operation is commenced, is in 85 such a position that the pawl-arm can not pass under the roller *n* when the vertical rod *d* is moved outward, the spring *q* will be compressed and remains compressed until the roller *n* during the running of the engine 100 again comes in a position, which permits engagement, whereupon the spring *q* at once draws the pawl-arm *l* under the roller, thereby causing the opening of the blow-off valve.

I claim:

1. In combination, an engine cylinder having a blow-off valve; a reversing mechanism; a lever connected to control said valve; a roller on said lever; and a movable device connected to be shifted automatically 110 by said mechanism during the reversing operation and itself engageable with said

roller at such time to rock said lever and thereby open the valve.

2. In combination, an engine cylinder having a blow-off valve; a reversing mechanism; a lever connected to control said valve; a roller on said lever; and a pivotally mounted pawl-arm connected to be shifted automatically by said mechanism during the reversing operation and itself engageable with said roller at such time to rock said lever and thereby open the valve.

3. In combination, an engine cylinder having a blow-off valve; an operating lever therefor; a rod for operating said lever; a cam shaft for operating said rod; a reversing mechanism connected to shift said rod during the reversing operation; and a device pivotally connected to the cylinder and adapted to be automatically shifted by said rod when the latter is shifted, said device operating said lever during its shifting movement to open said valve.

4. In combination, an engine cylinder having a blow-off valve; an operating lever therefor; a rod for operating said lever; a cam shaft for operating said rod; a reversing mechanism connected to shift said rod during the reversing operation; a pawl-arm pivotally connected to the cylinder and engageable with said lever to rock the same and thereby open the valve; and a connecting link between said rod and pawl-arm for operating the latter when the former is shifted by the reversing mechanism, said link being pivotally connected to said rod and pivotally and yieldingly connected to said pawl-arm.

5. In combination, an engine cylinder

having a blow-off valve; a controlling lever therefor; a movable device engageable with said lever to rock the same and thereby open the valve; a reversing mechanism; and connections between said device and said mechanism for automatically operating the former during the reversing operation, said connections comprising a link which is pivotally and yieldingly connected to said device.

6. In combination, an engine cylinder having a blow-off valve; a controlling lever therefor; a pawl-arm pivotally mounted on said cylinder and engageable with said lever to rock the same and thereby open said valve; a reversing mechanism; and connections between said pawl-arm and said mechanism for automatically operating the former during the reversing operation, said connections comprising a spring-pressed link pivotally connected to said pawl-arm.

7. In combination, an engine cylinder having a blow-off valve; a controlling lever therefor; a pawl-arm pivotally mounted on said cylinder and engageable with said lever to rock the same and thereby open said valve; a reversing mechanism; and connections between said pawl-arm and said mechanism for automatically operating the former during the reversing operation, said connections comprising a cylinder pivotally connected to the pawl-arm, a link extending therethrough, and a spring within the cylinder to act on said link.

In testimony whereof I affix my signature.

HANS HENRIK BLACHE.
